DESIGN FOR A PLAYING CARD

Emery E. Friedman, Chicago, Ill.

Application April 13, 1936, Serial No. 62,093

Term of patent 7 years

To all whom it may concern:

Be it known that I, Emery E. Friedman, a citizen of the United States, residing at Chicago, in the county of Cook and State of Illinois, have invented a new, original, and ornamental Design for Playing Cards, of which the following is a specification, reference being had to the accompanying drawing, forming part thereof.

The figure is a plan view of the back of a playing card, showing my new design.

I claim:

The ornamental design for a playing card, as shown.

EMERY E. FRIEDMAN.
